(57) **CLAIM**

The ornamental design of a rectangular train case, substantially as shown and described.

DESCRIPTION

FIG. 1 is a front perspective showing of the ornamental design for the rectangular train case of the present invention.

FIG. 2 is a front elevational showing of the ornamental design for the rectangular train case of FIG. 1.

FIG. 3 is a left side elevational showing of the ornamental design for the rectangular train case of FIG. 1. The right side being a mirror image of the left side.

FIG. 4 is a back elevational showing of the ornamental design for the rectangular train case of FIG. 1.

FIG. 5 is a top elevational showing of the ornamental design for the rectangular train case of FIG. 1; and,

FIG. 6 is a bottom elevational showing of the ornamental design for the rectangular train case of FIG. 1.

The subject matter shown in broken lines forms no part of the claimed design.
